BORING MACHINE.

1,418,923.

Specification of Letters Patent. Patented June 6, 1922.

Application filed May 18, 1918. Serial No. 235,337.

To all whom it may concern:

Be it known that we, CLARENCE M. HAVILAND and LEON C. BROWN, citizens of the United States, residents of Minneapolis, in 5 the county of Hennepin and State of Minnesota, have invented certain new and useful Improvements in Boring Machines, of which the following is a specification.

Our invention relates to manually operated machines for boring purposes generally but adapted particularly for re-boring the cylinders of internal combustion engines without removing the engine from the car, truck or tractor on which it may be mounted, or where, the cylinder head not being removable, the cylinders are detached and rebored through the lower end.

A further object is to provide a boring machine which can be easily and quickly mounted on a cylinder and the tools positioned readily for use.

A further object is to provide a machine having means for centering the tool carrier with respect to the cylinder to be rebored.

25 Other objects of the invention will appear from the following detailed description.

The invention consists generally in the constructions and combinations hereinafter described and particularly pointed out in the 30 claims.

In the accompanying drawings forming part of this specification,

Figure 1 is a vertical sectional view through the upper portion of a cylinder and a boring machine embodying our invention.

Figure 2 is a detail sectional view, showing a reboring tool at work in the upper end of the cylinder.

Figure 3 is a detail sectional view of the 40 upper portion of the boring machine,

Figure 4 is a sectional view on the line 4-4 of Figure 1,

Figure 5 is a sectional view on the line 5-5 of Figure 3,

45 Figure 6 is a sectional view on the line 6-6 of Figure 2,

Figure 7 is an edge view of the tool centering head.

In the drawing, 2 represents an internal 50 combustion engine cylinder, of any suitable size, having a flanged upper end 3 forming a seat for the base 4 of the boring machine. This base has webs 5 therein provided with cam slots 6 to receive bolts fitting therein 55 and in the holes in the flanged end of the

cylinder when the cylinder head has been removed. The shape and position of these slots allow the base to be adjusted and accommodate itself to the different positions of the bolt holes in the cylinder. 60

Upon the base a barrel 7 is mounted and secured thereto by suitable means, such as bolts 8. Within this barrel we arrange a sleeve 9 having a reduced exteriorly threaded lower end 10 on which is mounted a tool carrier 11. This carrier is provided with horizontal tool seats on which suitable boring tools 12 are mounted and secured in the usual way. The tool carrier is preferably made in two sections, an upper and a lower 70 one for convenience in forming the sockets for the tools, said sections being secured together after the tool sockets are formed by suitable means such as bolts 13. (See Figure 6). 75

For revolving the sleeve and tool carrier we provide a gear ring 14, locked on the sleeve by a key 15, said sleeve having a seat 16 therein to allow longitudinal movement of the sleeve in the gear ring. 80

A pinion 17 is secured to the upright shaft 18 which has bearings in brackets 19 and 20 on the barrel and the base 4, and is provided at its upper end with a beveled pinion 21 meshing with a similar pinion 22 on an operating crank 23. By operating this crank power will be transmitted to the sleeve 9 to revolve it and the lower carrier and tools. 85

At the upper end of the barrel is a yoke 24 supporting a screw 25, which depends 90 into the sleeve 9 and is provided with an annular groove 26 to receive a clamping screw 27 that is mounted in the yoke 24 for locking said screw against longitudinal movement. 95

A rod 28 is mounted in the upper end of the screw 25 for convenience in revolving the screw. The screw passes down through the upper end of the sleeve 9 and upon said end we mount a split washer composed of 100 internally threaded sections 29 and 30 mounted on the head of said sleeve by screw pivots 31, and said washer sections are provided with a tapered flange 32 exteriorly threaded to engage the threads of an internally threaded nut 33 mounted on said screw. When, therefore, the nut 33 is tightened or turned upon the flange the sections or wings of the split washer will be drawn together 110 to engage their threads with the threads of

the screw 25, and the screw being locked in the yoke 24, revolution of the sleeve will feed it downward to advance the boring tools to the work. Whenever desired, the 5 locking screw 27 may be released so that feed of the sleeve may be performed through the revolution of the screw.

In a machine or tool of this kind it is essential to provide some means for easily and 10 expeditiously centering the tool carrier with respect to the bore of the cylinder, and for this purpose we provide a centering head which we will now describe in detail.

34 represent a disc having a hub 35 formed therein which fits within a socket formed in the tool carrier, and within said hub we provide a laterally movable pin 36 having a round end to fit into a socket 37 in the tool carrier and held therein with 20 a yielding pressure by a spring 38. A downward pull on the centering head will disengage the pin from its socket and allow the removal of the tool. In mounting the tool in the carrier, the hub is pushed into the socket until the pin snaps into its socket and thereby the head will be temporarily held in place. The outer side of the disc is provided with an annular flange 39 having a tapered external surface 40. 41 is a split 25 ring which encircles the flange 39 and has a correspondingly tapered surface 42 to fit the tapered surface of said flange. The outer surface of said split ring is straight and adapted to fit against the wall of the cylinder and when said ring is pressed upwardly it will form a wedge between the walls of 30 the cylinder and the flange 39, and center the tool carrier accurately with respect to the bore of the cylinder.

40 For operating this split ring we prefer to form an exteriorly threaded hub 43 on the under side of the disc 34 and mount thereon a plate 44 having a loop 45 forming a hand grip by means of which the plate 44 45 may be revolved and moved into engagement with the ring 41, or separated therefrom. This centering head is used to determine the proper position of the tool or machine on the cylinder head preparatory to clamping it so 50 that accurate centering of the tool carrier will be insured, and when the tool has once been positioned and secured by means of its bolts passing through the slot 6, the operator may then reach up into the cylinder 55 through its open lower end, the piston having been removed, and grasping the handle 45 may release the split ring from its clamping position and pull the centering head down into and through the cylinder. The 60 plate 44 engages a pin 46 in the lower end of the hub 43, which forms a stop for said plate and prevents it from being separated from the hub in which it is mounted.

We claim as our invention:

65 1. A boring machine comprising a base

having means for mounting it on an engine cylinder, a barrel supported by said base, a sleeve mounted within said barrel and vertically movable therein, a tool carrier supported by the lower end of said sleeve, a 70 shaft mounted in said base and geared to said sleeve for revolving it, a yoke mounted on said barrel, and a screw mounted in said yoke and depending within said sleeve and having threaded engagement therewith. 75

2. A boring machine comprising a base having means for securing it on the work to be bored, a tool carrier supported in said base and having seats for boring tools, a centering device comprising a disc having a 80 hub and spring-pressed means for temporarily securing it in said tool carrier, also disc having a flange provided with an externally tapered surface, a split ring encircling said flange and having an oppositely inclined 85 tapered surface to engage the surface of said flange, and means for expanding said ring to seat it against the walls of the surface to be bored and center said base and tool carrier thereon. 90

3. A boring machine comprising a base having means for securing it on the work, a tool carrier mounted in said base and having seats for boring tools, a centering head comprising a disc having a hub and means 95 for detachably connecting it to said tool carrier, said disc having a depending externally threaded member, a plate internally threaded and movable thereon and provided with an operating handle, and means actuated by the movement of said plate for centering said disc and said tools with respect to the surface to be bored. 100

4. A boring machine comprising a base having means for securing it on the work to 105 be bored, a tool carrier supported in said base and having seats for boring tools, a centering device comprising a disc having a hub and means for temporarily securing it in said tool holder, said disc having a flange 110 provided with a tapered surface and a split ring encircling said flange and having an oppositely inclined tapered surface to engage the surface of said flange, and means for expanding said ring to seat it against the walls 115 of the surface to be bored and center said base and tool carrier thereon.

5. A boring machine comprising a base having means for securing it on the work, a tool carrier mounted in said base and having 120 seats for boring tools, a centering head comprising a disc having a hub and means for detachably connecting it to said tool carrier, a plate having threaded engagement with 125 said disc and movable thereon and provided with an operating handle, and means actuated by the movement of said plate for centering said disc and said tools with respect to the surface to be bored. 130

6. A boring machine comprising a base 130

having means for securing it on the work to be bored, a tool carrier supported in said base and having seats for boring tools, a centering device and spring-pressed means 5 for temporarily securing it in said tool carrier, said centering device including a flange provided with an internally tapered surface, a split ring encircling said flange and having an opposite inclined surface to engage 10 the surface of said flange, and means for expanding said ring to seat it against the walls of the surface to be bored and center said base and tool carrier thereon.

7. A boring machine comprising a base 15 having means for securing it on the work to

be bored, a tool carrier supported in said base and having seats for boring tools, a centering device, a spring-pressed means for temporarily securing it in said tool carrier, an operating handle for said centering device accessible through the open end of the article being bored, said spring pressed means being also accessible through said open end for disengaging said centering device when said tool carrier has been centered 20 with respect to the work.

In witness whereof, we have hereunto set our hands this 4th day of May, 1918.

CLARENCE M. HAVILAND.

LEON C. BROWN.
